DECORATIVE SCROLL

Garland L. Sheldall, Los Angeles County, Calif.
(9063 Nagle Ave., Panorama City, Calif.)

Filed Nov. 10, 1965, Ser. No. 88,058

Term of patent 14 years

(Cl. D54—2)

FIGURE 3 is a typical sectional view of the decorative scroll of FIGURE 1 as taken in the direction of arrows 3—3 illustrating the thickness thereof.

I claim:

The ornamental design for a decorative scroll, substantially as shown and described.
